UNITED STATES PATENT OFFICE.

ALEXANDER B. CARSTENS, OF MONTEREY, MEXICO, ASSIGNOR TO THE AMERICAN METAL COMPANY, LIMITED, OF NEW YORK, N. Y., A CORPORATION OF NEW YORK.

REVOLVING SEPARATOR.

1,331,802.

Specification of Letters Patent. Patented Feb. 24, 1920.

Application filed October 1, 1918. Serial No. 256,437.

To all whom it may concern:

Be it known that I, ALEXANDER B. CARSTENS, a citizen of the United States, residing at Monterey, N. L., Mexico, have invented certain new and useful Improvements in Revolving Separators; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a separator for use in connection with metallurgical furnaces where the molten mass contains two or more ingredients of different specific gravity which it is desired to separate by allowing the heavier ingredients to settle to the bottom, keeping the mass liquid or mobile by applying additional heat to the surface of the bath, and tapping off the heavy matter at the bottom and the lighter near the surface of the bath, thereby making the settling process practically a continuous operation. In this application the invention will be considered with special reference to its use in connection with lead smelting furnaces. In the every day operations of a lead blast furnace, it is not always possible to make the slag clean enough so that it can with safety be tapped from the blast furnace and immediately disposed over the slag dump. The present practice is to make as clean a lead silver bullion as possible. This process may actually be taking place within the furnace, but its interior physical condition may be such that the reduced lead cannot settle to the lead well, so it runs off with the slag. Furthermore, the metallurgist desires as a rule to get a certain "matte fall", that is, by adding sulfur to the charge, the sulfur combines readily with the copper if there is any in the charge and combines freely also with the iron. This matte is a "good collector of values". Hence, it is desirable to bring the slag and matte into intimate contact and to have it remain so for a reasonable length of time in practically a quiet state in order to allow all the values to settle out and be taken up

by the matte. To produce this condition the slag separator was introduced.

The first separators were large, rectangular brick affairs held together with buckstays and tie rods. They also had cooling pipes built into the brick work to keep the side walls and bottoms reasonably cool. There were times, however, when the separator would "freeze up". The only thing to be done then was to partially dismantle the separator and clean it. This usually is a most expensive proceeding. A modification of the separator idea is to put a matte box or settler in front of each blast furnace, but as these as a rule, are not fired, they soon freeze up and have to be changed frequently. Furthermore, there are usually other elements which enter into the separator, such as arsenic and zinc. The arsenic combines with iron and sulfur and makes "speiss", while the zinc combines with sulfur and makes "zinc mush", the worst enemy of the separator. The order in which these mixtures usually lie in the separator when settled out is as follows:

Slag—top.

Zinc mush.

Speiss.

Matte.

Lead—bottom.

When a separator freezes, practically everything below the slag line solidifies and in this condition the separator cannot perform its work. In a fired separator the roof is the hottest and the bottom the coolest part of the furnace.

My improved construction as illustrated in the drawing consists of a steel shell mounted to revolve so that if the separator should freeze up it is only necessary to give the shell a half turn which will bring the extra slag, matte and lead taps into their respective positions and the heat will gradually melt out the old bottom which by the process of turning the shell half over has been placed in the roof. This is the vital feature of the invention.

Hence, my improvement is intended to overcome the difficulties incident to the freezing up of separators of the construction heretofore in vogue and as hereinbefore explained.

Having briefly outlined my improvement as well as the difficulties it is intended to overcome, I will proceed to describe the same in detail reference being made to the accompanying drawing in which is illustrated an embodiment thereof. In this drawing:

Figure 1 is a vertical longitudinal section of my improved revolving separator, the section being taken on the line 1—1, Fig. 2 looking toward the right.

Fig. 2 is a view partly in end elevation and partly in section, the section being taken on the line 2—2, Fig. 1 viewed in the direction of the arrows.

Fig. 3 is a side elevation of my improved separator, being a view looking in the direction of the arrows 3—3, Fig. 2.

Fig. 4 is an end elevation of the same or 20 a view looking in the direction of arrows 4, Fig. 3.

Fig. 5 is a top plan view of my improved separator, illustrating a modified form of construction for imparting the necessary rotary, or partially rotary, movement to the 25 cylinder.

The same reference characters indicate the same parts in all the views.

Let the numeral 5 designate the shell of 30 my improved separator, this shell being provided with end heads 6 and 7 and equipped with circumferentially arranged tires 8 engaging rollers 9 for purposes of rotation. The head 7 as shown in the drawing is provided with a pulley 10 which is engaged by a belt 12 for the purpose of moving the furnace rotatably when for any reason it may be desirable so to do.

The shell 5 is provided with a refractory 40 lining 13 which covers the curved walls and also the heads of the shell. The head 6 is provided with an opening 14 for the introduction of the fuel burner 15; while the head 7 is provided with an opening 16 for 45 the introduction of the slag. This opening also serves as an escape for the products of combustion. The head 6 at the firing end of the separator is provided with a double set of lead and matte taps, the lead taps being designated by the numeral 17 and the matte taps by the numeral 18. These sets of taps are diametrically arranged. The shell is further provided with two slag taps each of which is designated by the numeral 19, 50 the lower slag tap being always under the line of the slag bath 20. The two slag taps are also diametrically opposite, one being always below and the other above the line of the slag bath.

Under normal operating conditions, slag 60 is poured into the separator through the opening 16 and by way of a chute or conduit 21 until it reaches the line or level 20 (see Fig. 1). After the slag has been at 65 rest for a while, the heavier ingredients will

be settled down so that the slag can be tapped out at the lower slag tap 19 into a slag pot or other suitable receptacle suitably arranged for the purpose but not illustrated in the drawing.

When a sufficient amount of lead and matte has collected, it may be removed by way of the taps 17 and 18.

If the separator should freeze up all that is necessary is to give the shell a half turn 75 which will bring the extra slag, matte and lead taps into their respective positions and the heat will gradually melt out the old bottom which by the process of turning the shell half over has been placed in the roof as heretofore explained.

It is not necessary that this separator should be cylindrical in shape, since it may be polygonal, rectangular or elliptical; or any combination of shapes necessary to 85 produce the desired metallurgical results. It need not necessarily be mounted on tires for turning; since it may be suspended or mounted to rotate on trunnions.

In Fig. 5 I have illustrated a hand-manipulated winch, or drum, for imparting the rotary movement to the cylinder, as circumstances may require. This form is believed preferable to the belt construction shown in the other views, since the heated condition 95 of the cylinder might interfere with the throwing on and off of the belt, even though the latter were made of noncombustible material.

In Fig. 5, let the numeral 25 designate a 100 winch considered in its entirety and composed of bearing uprights, 26, a drum, 27, journaled in said uprights, a gear, 28, on the drum, the smaller gear, 29, meshing with the gear 28, the gear 29 being fast on a shaft, 105 30, suitably journaled and having crank handles, 31, at its opposite extremities. A cable, 32, is wrapped around the cylinder and also around the drum, 27, of the winch, so that as the winch is rotated, the drum 110 will be actuated as desired. The speed-reducing construction disclosed in Fig. 5 makes it practicable to operate the cylinder by hand, as will be readily understood. It is preferred that the cylinder should be provided midway between its extremities with a circumferential track, 33, which will maintain the cable in position at all times.

What I claim is:

1. A separator for molten materials of 120 differing specific gravity, comprising a rotatable shell having two sets of tap holes occupying a diametrically opposed relation to each other, axially disposed means for directing heat to the interior of said shell and means for rotating said shell to permit the utilization of either set of tap holes.

2. A separator for molten materials of 125 differing specific gravity, comprising a rotatable shell, having two sets of tap holes oc-

cuping a diametrically opposed relation to each other, the tap holes of each set being spaced diametrically of said shell, axially disposed means for directing heat to the interior of said shell and means for rotating said shell to permit utilization of either set of tap holes.

3. A separator for molten materials of varying specific gravity, comprising a metal shell having a lining of refractory material and having an axially located opening at each end, the shell having two sets of tap holes, the number and position of each set corresponding with the different materials to be handled by the separator, the two sets being oppositely located diametrically and the shell being movable to bring the two sets alternately into position for use.

4. A separator for molten materials of varying specific gravity comprising a metal shell having a lining of refractory material and having an axially located opening at each end, one opening being adapted to

receive molten material and permit the escape of products of combustion, while the 25 opening at the other end is adapted to receive a burner for supplying heat, the shell having two sets of tap holes, the number and position of each set corresponding with the number and kind of different materials to be 30 handled, the two sets being oppositely located and the shell being movable to bring the said sets alternately into position for use.

5. A separator for molten materials of 35 differing specific gravity, comprising a rotatable shell, axially disposed openings in the ends of said shell for introducing material and heat to the interior of said shell, two sets of tap holes diametrically opposed in the ends of said shell and means for rotating said shell to permit utilization 40 of either set of tap holes.

In testimony whereof I affix my signature.

ALEXANDER B. CARSTENS.
